ABSTRACT

This invention relates to an electro-optical system capable of determining the transnational shift of one image of a given scene with respect to another image obtained a short time before. This is accomplished by measurement of the amount of electrons impinging on phosphor screen 30 from a particular direction.

IMAGE CORRELATOR WITH IMAGE SHIFT DETECTION CAPABILITY

The invention herein described may be manufactured and used by or for the Government of the United States of America for governmental purposes without the payment of any royalties thereon or therefor.

The present invention relates to image correlator and the method of correlating images electronically.

This invention relates to an electro-optical system capable of determining the translational shift of one image of a given scene with respect to another image obtained a short time before. The reference image is stored on a storage electrode in a novel vacuum tube arrangement. The image to be compared is focused onto a different plane than that of the storage electrode. Effectively, the two images are superimposed and electrons are allowed to pass through to the viewing screen and excite a spot in the direction of "best match" of the two images. The deviation of the spot is a measure of the shift of the image over the time of a cycle of operation of the device.

Accordingly an object of the invention is to provide a means and method of the electronic correlation of two images.

Other objects and many of the attendant advantages of this invention will become readily appreciated as the same becomes better understood by reference to the following detailed description when considered in connection with the accompanying drawings wherein:

FIG. 1 is a schematic cross-sectional view of an image correlating tube incorporating one embodiment of the invention.

FIG. 2 is a diagram showing the focusing in a plane of an image released from the photocathode of the tube of FIG. 1.

Referring now to the drawing, the image comparing device is provided with an evacuated envelope 10 which contains various electrodes to be described below. As shown in FIG. 1, a light image from object 12 is focused by means of a suitable lens 14 onto a photocathode 16, which in response to said light image, emits a corresponding electron image. The electron image is directed by suitable means, such as by focusing coil 18 and accelerating electrode 20 onto a storage electrode 22. Storage electrode 22 consists of a back plate 24 and a dielectric 26 which may be of the type used in the recording storage tubes (CK7571). A second focusing coil 28 and a fluorescent screen 30 are provided to focus and view the stored image. All electrodes of tube 10 are connected to a programmable power supply 32 which provides the necessary voltages for the different electrodes of the tube. Power supply 32 is connected to a programmer 34 which determines the sequence of the different program modes described below. Programmer 34 may be manually operated.

When tube 10 is operated in the erase mode, photocathode 16 is uniformly illuminated by a light source 36 and all the electrode voltages and focusing means are adjusted so as to remove all charges from storage screen 22. In this mode, electrons are released from electrode 16 and flood storage screen 22 in such a way that either by secondary emission from storage screen 22 or by electron bombardment induced conductivity of storage screen 22, all charges are removed from electrode 22.

When operated in the store mode, an image from the scene 12 is focused by lens 14 onto electrode 16. By properly adjusting the electrode voltages and the focusing coils, the emitter photoelectrons from electrode 16 are electronically focused onto storage screen 22 and will cause a change in the distribution of electrons on screen 22. This distribution of electrons will remain as a stored image which may be of either negative or positive polarity. The size of this stored image need not be of the same size as the image on electrode 16.

Next, tube 10 is operated in the viewing mode where again electrode 16 is uniformly illuminated by light source 36. Focusing coil 18, accelerator 20 and storage screen 30 are adjusted so that no change in the electron distribution of storage screen 22 will result. Electrode 22 is now uniformly illuminated by flood electrons from photocathode 16. Storage screens should be selected of the types that have the property of permitting a larger or smaller flow of electrons through the screen 22 depending on the charge stored thereon. As a result, the pattern of electrons released from electrode 22 will be similar to the pattern of electrons released from electrode 16 during the store mode. By the proper adjusting of focusing coil 28, this electron image is focused onto phosphor screen 30 which is identical to the stored image and can be viewed by an operator. The above described three functions, erase mode, store mode, and viewing mode are functions well known in the art and may be as shown and described in U.S. Pat. No. 2,992,346.

When operated in the correlation mode, electrode voltages and focusing coils 18 and 28 are adjusted so that the electron image from photocathode 16 is focused into a plane which is not common with the storage screen 22. While several different arrangements are possible depending upon the particular spacing of the elements in the tube, two examples of the correlation mode are described below.

In the first example, the electron image released from electrode 16 may be focused into a plane 38 between accelerator electrode 20 and storage screen 22 (See FIG. 2). Focusing coil 28 and the electrode voltages in the right half of the tube should be adjusted so that there will be no further acceleration of the electrons leaving the image plane between electrode 20 and electrode 22. Since electrons from the different spots of electrode 16 will be released in practically all directions (to the rear of electrode 16), the same will be true for the electrons leaving the image plane between electrodes 20 and 22. Focusing coil 18 and the electrode voltages in the left section of the tube are adjusted so that the virtual image is larger than the stored image on storage screen 22. With electrons leaving in all directions from the virtual image 38, electrons will be allowed to penetrate storage screen 22 depending upon the charge stored thereon. Depending upon whether or not the two images in a particular direction match, a certain amount of electrons will hit phosphor screen 30 in this particular direction. As shown in FIG. 2, the size of virtual image 38 is larger than the size of the stored image on storage screen 22. This geometry will cause the electron passing through screen 22 to converge at the spot 40 on phosphor screen 30. Analogous to the matching of transparencies described in U. S. Pat. No. 2,787,188, the number of electrons

will be largest or smallest in the direction of best match depending upon whether a negative or positive image was stored on the electrode 22 during the store mode. The deviation of the correlation spot 40 (FIG. 2) on screen 30 is a measure of the translational shift of the image of scene 12 on photocathode 16 between the time this image was stored in the store mode and the image is correlated in the correlation mode.

In the second example, focusing coil 28 is adjusted to act as an electron lens to form a visual image between electrodes 20 and 22 which would be smaller than the image stored on electrode 22. The remainder of the operation is identical to that described in example one above.

Various modifications may be made in the practice of the invention. Light source 36 may be arranged in a ring around tube 10 in back or in front of electrode 16. In one form the ring of light may be a band of electro-luminescent material on envelope 10.

Light source 36 may also be replaced by an electron flood gun inside envelope 10.

Photocathode 16 may be sensitive in the ultra-violet, in the visible and/or in the infrared portion of the electromagnetic spectrum.

The electrode for electrostatic focusing may be formed by coating the inside of tube 10 with a conductive material.

Phosphor screen 30 may be replaced by an electronic scanning device such as an electron bombardment induced conductivity target and a television scan readout, such as used in vidicons, image orthicons, etc. The conductivity target may have a resistor backing with four electrodes positioned thereon to detect the position of the correlation spot. Phosphor screen 30 may also be optically coupled to a television pick-up tube.

The present invention may be used in a system for automatic tracking of scenes, such as would be used in an electro-optically guided air-to-surface missile. Since the image in this case will not only experience translational motion on photocathode 16, but considerable other changes such as magnification, it is necessary to up-date the stored reference image on storage screen 22 periodically. This up-dating can be done most accurately if the correlation spot is exactly in the center of phosphor screen 30 or the other device that may replace it. For low-light level images tube 10 may contain one or more intensifier sections between photocathode 16 and accelerator 20.

Obviously many modifications and variations of the present invention are possible in the light of the above teachings. It is therefore to be understood that within the scope of the appended claims the invention may be practiced otherwise than as specifically described.

What is claimed is:

1. The method of electronically correlating two images comprising the steps of:

a. uniformly illuminating a direct view type storage

tube,

- b. adjusting the electrode voltages of the tube to remove all charges from the storage screen of said storage tube,
- c. adjusting the electrode voltages and focusing means to cause an image of a scene to be optically focused on the photocathode of the tube and to be electronically focused on the storage screen,
- d. adjusting the electrode voltages and focusing means to focus a subsequent electron image of the scene that is different in size from that focused on to the storage screen into a plane which is not common with the storage screen,
- e. observing on the phosphor screen the point at which electrons are permitted by the storage screen to impinge on the phosphor screen.

2. The method of electronically correlating two images comprising the steps of:

- a. uniformly illuminating a direct view type storage tube,
- b. adjusting the electrode voltages of the tube to remove all charges from the storage screen of said storage tube,
- c. adjusting the electrode voltages and focusing means to cause an image of a scene to be optically focused on the photocathode of the tube and to be electronically focused on the storage screen,
- d. adjusting the electrode voltages and focusing means to focus a subsequent electron image of the scene in a plane between the accelerating electrode and the focusing screen so that the "virtual" image formed is larger than the image on the storage screen,
- e. observing on the phosphor screen the point at which electrons are permitted by the storage screen to impinge on the phosphor screen.

3. The method of electronically correlating two images in a direct view type storage tube comprising the steps of:

- a. uniformly illuminating the photocathode of said storage tube for removing all charges from the storage screen of said storage tube,
- b. removing the illuminating source from said photocathode after the charge has been removed from the storage screen,
- c. adjusting the electrode voltages and focusing means to cause an image of a scene to be optically focused on the photocathode and to be electronically focused on the storage screen,
- d. re-adjusting the electrode voltages and focusing means to focus a subsequent electron image of the scene into a plane intermediate said storage screen and said photocathode so that the "virtual" image formed is larger than the image on the storage screen,
- e. observing on the phosphor screen the point at which electrons strike the screen indicating the point of best match between the two images.
